UNITED STATES PATENT OFFICE.

ERVIN E. STRAWN, OF CLEVELAND, OHIO, ASSIGNOR TO ARTHUR S. GILMAN, OF CLEVELAND, OHIO.

DUPLICATING DEVICE.

Application filed November 6, 1925. Serial No. 67,386.

My invention relates to devices for making a copy or copies of matter written or typed upon an original sheet, its object being to effect such result in an efficient and economical manner.

The invention may be advantageously applied to a typing machine and thereby eliminate the use of a carbon paper sheet for making a carbon copy.

10 The general object of my invention is accomplished by providing a platen having a surface of such character that a transferable carbon material may be applied thereto in sufficient amount to permit impressions 15 to be made upon the backs of a considerable number of sheets laid in succession thereon, without further application of such material and without smudging the said backs of the sheets.

20 By platen I mean a base member of sufficient stiffness to maintain uniformity of its contour while being manipulated and which may form a firm base for receiving the pressure of the writing or printing instrument, 25 in contradistinction to a sheet of carbon paper which is extremely flexible, folds and wrinkles easily while being handled and cannot of itself form such a base.

30 The said invention consists of means hereinafter fully described and particularly set forth in the claims.

35 The annexed drawings and the following description set forth in detail certain means for carrying out my invention, the disclosed means, however, constituting but one of the various mechanical forms in which the principle of my invention may be employed.

In said annexed drawings:

40 Figure 1 represents a perspective of a simple form of my invention, showing an original record sheet and a copy thereof in position on the device.

45 Fig. 2 represents a fragmentary enlarged and exaggerated cross-section.

Fig. 3 represents a plan of a fragmentary portion of a typewriting machine embodying my said invention as applied thereto.

50 Fig. 4 represents a section taken upon the plane indicated by line IV-IV in Fig. 3.

55 Referring first to the form of my invention illustrated by Figs. 1 and 2, I provide a flat platen 1 made of any suitable material such as a sheet of brass or steel and having a roughened surface forming a multiplicity of minute wells as shown in Fig. 2.

This roughened character of surface may be inherent in the material from which the platen is made or may be imparted thereto by etching, sand blasting, or any other suitable manner.

60 I then apply to such surface a transferable solid and hence dry carbon material consisting of a suitable wax having coloring matter such as lamp-black, incorporated therein in the required amount and which may be in the form of a cake. This material is spread over the entire surface of the platen by rubbing the cake thereon, and the platen then wiped so as to remove the superfluous carbon material, spread same 70 uniformly upon the platen, and just fill the wells or depressions.

A sheet of paper 2 such as tissue paper, is laid upon the platen and the original sheet 3 is laid upon it, as shown in Fig. 1.

75 Matter may now be written upon the upper surface of the sheet 3 and the pressure transmitted to the sheet 2 and the platen surface, in so doing, causes the carbon material of the platen to be transferred to the back of sheet 2 to reproduce the written matter on such sheet back. This matter may be read from the front face of said sheet 2, thereby permitting the latter to be used as a copy.

80 In applying my invention to a typewriting machine, I provide the usual cylindrical platen 4 with a roughened surface as described in connection with the previously described flat platen. To this surface I apply the carbon material, and wipe same as before. Such application may be made by holding the cake of carbon material against the platen surface and then turning it by hand. The wiper may then be held against the surface and the platen likewise turned by hand.

85 A translucent sheet 2 and a superposed original sheet 3 are inserted in the machine with the sheet 2 in contact with the platen 90 as shown in Fig. 4.

95 The machine now being operated to type the original sheet 3, impressions of the characters will be made upon the back of sheet 2 and the latter hence will form a copy.

100 I have found that quite a large number of copies may be made with but a single application of carbon material.

105 I have also found that when the invention is applied to a typewriting machine, it op-

erates with particular success when applied to a machine employing what I shall term a "right-line" type-bar, that is a type-bar whose path of movement is in a straight line, 5 and I have illustrated the invention as applied to such a machine. What is known in the trade as the "Noiseless" typewriter, is a machine employing such a type-bar.

In order to always have the carbon material and wiper ready to hand a holder 5 may be provided in which the cake 6 of carbon material may be inserted so as to extend along the platen 4. The holder may be pivotally mounted upon two swinging arms 7—7 15 pivoted upon the frame of the typewriting machine, as shown in Figs. 3 and 4. This holder may have associated with it a wiper 8 consisting of a flexible strip of material such as rubber.

20 By means of this arrangement, either the cake 6 or wiper may, when required, be applied to the platen, and when not in use be swung up out of position, as shown in dotted lines in Fig. 4, where it may be held by any 25 suitable means (not shown).

The term "carbon material" as herein used, is intended to include any transferable solid material similar to that used to make carbon paper and which may be of any desired color 30 required to contrast with the color of the paper on which the copy is made.

What I claim is:

1. In a typewriting machine, the combination with a cylindrical platen having a surface adapted to receive and retain a transfer material; of a bar of such material in solid 35

form, mounted upon the typewriter and movable toward and from said platen, whereby said material may be applied to the latter when required. 40

2. In a typewriting machine, the combination with a cylindrical platen having a surface adapted to receive and retain a transfer material; of a bar of such material in solid form and substantially longitudinally coextensive with said platen, mounted upon the typewriter and movable toward and from the platen, whereby substantially the entire surface of the latter may be supplied with said material when required. 45

3. In a typewriting machine, the combination with a cylindrical platen having a hard permanent surface roughened to form minute wells; of a bar of solid transfer material mounted on the typewriter and movable toward and from such platen, whereby such material may be applied to the latter as required. 50

4. In a typewriting machine, the combination with a cylindrical platen having a hard permanent surface roughened to form minute wells; of a frame movably mounted in proximity to said platen and carrying a holder pivotally mounted on said frame, and provided on one side with a bar of solid transfer material and upon the other side with a wiper, whereby either the bar or wiper may be applied to the platen as required. 55

Signed by me this 31st day of October, 1925.

ERVIN E. STRAWN.
